ELECTRIC IRON

Robert O. Ernest, Oak Park and Donald E. Leman, Glen
Ellyn, Ill., assignors to Sunbeam Corporation, Chicago,
Ill., a corporation of Illinois

Filed Sept. 24, 1963, Ser. No. 76,705

Term of patent 14 years

(Cl. D49—6)

FIG. 1.

FIG. 2.

FIG. 3.

FIG. 4.

FIG. 1 is a side elevational view of an electric iron embodying our new design;

FIG. 2 is a front elevational view thereof;

FIG. 3 is a rear elevational view thereof; and

FIG. 4 is a top plan view thereof.

The dominant features of our design reside in the portions shown in full lines.

We claim:

The ornamental design for an electric iron, as shown and described.
